(57) **CLAIM**

The ornamental design for a light therapy headwear, as shown and described.

DESCRIPTION

FIG. 1 illustrates a front perspective view of a light therapy headwear;

FIG. 2 illustrates a back perspective view of the light therapy headwear thereof;

FIG. 3 illustrates a bottom perspective view of the light therapy headwear thereof;

FIG. 4 illustrates a front view of the light therapy headwear thereof;

FIG. 5 illustrates a back view of the light therapy headwear thereof;

FIG. 6 illustrates a left side view of the light therapy headwear thereof;

FIG. 7 illustrates a right side view of the light therapy headwear thereof;

FIG. 8 illustrates a top view of the light therapy headwear thereof;

FIG. 9 illustrates a bottom view of the light therapy headwear thereof; and,

FIG. 10 illustrates a left side view of the light therapy headwear thereof shown in use.

The broken line showing of the person in FIG. 10 illustrates environment and forms no part of the claimed design. The remaining broken lines in the drawings illustrate portions of the light therapy headwear that form no part of the claimed design.

1 Claim, 10 Drawing Sheets
